SPECIFICATION forming part of Design No. 25,374, dated April 7, 1896.

Application filed March 6, 1896. Serial No. 582,140. Term of patent 3½ years.

To all whom it may concern:

Be it known that I, JOHN B. NEIL, a citizen of the United States, residing at New York, in the county of New York and State of New York, have invented and produced a new and original Design to be Wrought into Wilton and other Carpeting in such Coloring as may be Designed, of which the following is a specification.

This invention comprises two parts—namely, the design A for a carpet-body and the design B for a border; and I do hereby declare that the drawing accompanying this specification gives and conveys to any one skilled in the art of carpet weaving and manufacture a clear understanding of same, and is sufficient to enable such person to use my invention.

The body A shows alternate oval-shaped

figures of Egyptian style. The border B shows Egyptian columns with ornamentation, and also similar figures to those of body.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A and the border B, substantially as shown.

In testimony whereof I have hereunto set my hand in the presence of two subscribing witnesses.
